JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

LATCH MECHANISM.

Application filed September 18, 1924. Serial No. 738,344.

This invention relates to improvements in latch mechanism of a new type devised by me especially to meet the problems encountered in connection with the doors of closed automobile bodies. The type is exemplified so far as known to me at the present time only in my first filed application, Serial Number 683,144, filed December 28, 1923, for improvements in latch mechanism. The present invention consists of an improvement in the type which I have heretofore evolved, as set forth in the recited application.

The prime object of this type of lock is to enable manufacturers to embody in their cars a door window pane of substantially the full width of the door. Stated conversely, the prime object is the reduction to a veritable minimum of the opaque projection of the combined door post and door rail above the window ledge. This results in material enlargement of the range of vision. From a constructional point of view, the object is to have the window pane lie as closely against the door jamb as possible, and thereby to simplify, lighten and cheapen construction. These ends were interfered with and prevented heretofore by the embodiment of the latch operating mechanism in a unitary structure or the use of latch operating spindles which projected all the way through the door, either or both the latch operating mechanism and the spindle lying directly in the path of any window pane which it might be sought to make substantially equal to the width of the door.

According to the invention of my pending application, I evolved a new type of lock when I divided the latch operating mechanism into inside and outside latch operating devices spaced apart whereby the window pane could be interposed, and the coordinating of the separated latch operating devices through an interlocking member in the form of a swinging bolt mounted on the edge of the door and commonly engaged by said separated latch operated devices. This construction enabled me to get the window pane very close to the door rail if not actually up against it, and at the same time to get the door rail fairly close to its jamb in the closure of the door with the result that I re-

duced the opaque projection of the door rail and door post approximately fifty per cent.

The present invention enables me to attain the prime object of the invention to an even greater degree. According to this present invention, I adapt the bolt or other interlocking member for the two, independent and separated latch-operating devices to be mounted upon the door post instead of upon the edge of the door, but retain each of the two latch-operating devices upon the door.

A number of advantages flow from this improvement. First of all by this removal of the bolt or other interlocking member from the edge of the door, where there is little room, to the post, this member may have its body disposed substantially wholly within the body of the post where there is ample room, and the space between the door rail and the post may unquestionably be maintained at that minimum consistent with good clearance for closure. This brings the door closer to the post and reduces opaque projection. Moreover, the bolt being mounted on the post, there is no necessity for cutting the web on the door rail, nor for providing internal clearance for a bolt which operates through the web. The rail section may therefore be made thinner and the pane may lie actually over against the web of the door rail. Still further reduction in opaque projection results.

Moreover, since there is ample room in the interior of the post (the post being as a rule wide enough to accommodate the overlap of two adjacent doors), design in more generous and more efficient proportions becomes possible, and simplification results, derived jointly from this fact and the fact that locking members pertaining to adjoining doors may be co-ordinated and the number of parts decreased. Marked advantage is derived from the general simplicity of construction of the latch-operating devices. The inside operating device I construct as a simple knife type bolt interlocking with the swinging bolt on the post. The outside operating device I construct like a roll back of the simplest type. Both of these devices engage the bolt or other locking member freely and without the complexity of multiple articulation. There are thus fewer parts

in the latch-operating devices, and these few may be made of more generous and exact proportions. Neatness and compactness follow. Manufacturing cost is lowered and 5 efficiency is raised.

I shall illustrate and describe that embodiment of my invention best known to me at the present time. It has the capability of being embodied in a large number of forms 10 as will be readily discerned upon the full understanding of its character.

Of the drawings, Fig. 1 is a view in front elevation of the side of an automobile having a sedan body, in the adjacent doors of which 15 my invention is embodied.

Fig. 2 is a horizontal section of the post and the adjoining doors showing my invention in plan.

Fig. 3 is a front elevation of that one of 20 the latch-operating devices in the form of a roll back, taken on the line 3-3 of Fig. 2.

Fig. 4 is a sectional elevation taken on the line 4-4 of Fig. 2.

Fig. 5 is a front elevation of the other 25 one of the latch-operating devices in the form of a bolt, and taken on the line 5-5 of Fig. 2, and

Fig. 6 is a transverse section taken on the 30 line 6-6 of Fig. 5.

Fig. 7 is a perspective view of the interlocking bolt.

Fig. 8 is a plan view of a modified form 35 of interlocking bolt, with the post in which it is mounted indicated in outline.

Fig. 9 is a section of the post on the line 9, 9 of Fig. 1.

The details of my invention are shown in 40 Fig. 2 largely as applied to one door only, but it will be understood that, while so shown and so described in the main, a similar lock mechanism is to be provided in connection with the adjacent door.

The sides of sedan bodies in general are 45 usually provided with a center post 10 against which the front and rear doors 11 and 12, respectively, close. The side walls 13 and 14 of the post, respectively, constitute the door jambs. The door frames comprise vertically-extending jamb rails 15 and 50 16, and closing edges 16 and 17 which overlap the front face of post 10 and effect a neat closure on the jamb openings or cracks. Window panes 18 and 19 constitute closures for the door windows and may be lowered 55 into the lower body of the door, and raised therefrom by suitable mechanism (not shown).

Above the waist of the body, the only 60 opaque projection in the line of vision forward of the tonneau is constituted by posts 10 and the associated door rails and connected parts 15 to 17, and by the front posts of the body. The freedom of vision from the interior of the body is measured by the narrowness of these parts. It has been pos-

sible to make the front posts quite narrow because the front doors have only a hinged engagement therewith and the windshield need not necessarily have a wide frame, but until my evolution of the type of lock to 70 which this appertains, it has not been possible to make the intermediate posts 10, and adjoining parts, sufficiently narrow to enable one to greatly reduce even the section of the front posts without impairing the symmetrical design of the car, thereby detracting from its appearance. Reduction of the posts 10, and adjoining parts, has not been feasible because the lock-operating devices have not been of such form as to permit the 75 window panes 18 and 19 to be raised and lowered through them. It was necessary to support the window panes beyond the borders of the lock-operating device, and this support necessitated wide opaque members 80 above the waist line of the body.

In the application on file, I show a type. 85 of lock embodying independent and separated inside and outside latch-operating devices, and window panes supported between 90 them so they can be freely raised and lowered without interfering with the locking functions. The width of the projected area above the waist line is therefore rendered independent of the latch-operating 95 devices, and dependent solely upon the combined thickness of the window pane support and jamb rail, such interlocking means as may be provided between the inside and 100 outside latch-operating devices, the closeness of fit of the door to the jamb, and the actual width of the post 10 itself. The present invention, like the former, not only eliminates the former dependency, but reduces markedly the degree of the latter dependencies.

The latch mechanism of the present invention comprises an outside latch-operating 110 device 20 and an independently operable inside latch-operating device 21 spaced therefrom, together with an interlocking member 22 mounted on the post 10. In the embodiment shown, this interlocking member is in the form of a horizontally-swinging bolt 115 mounted on a vertical axis or pintle 23. This axis is located toward the exterior of the post 10 and is provided with an engaging portion 24 which faces inwardly. A spring 25 biases bolt 22 outwardly from the jamb 120 13.

Latch-operating means 21 is also in this embodiment in the form of a swinging bolt, but instead of swinging in a horizontal plane, as does bolt 22, it is mounted on a horizontal axis 26 to swing in a vertical plane, and is operable by handle 27 from the interior of the car to swing the engaging portion 28 upwardly out of engagement with co-acting portion 24 of bolt 22 against the pressure of retaining spring 28*. This 125 130

type of bolt may be called a knife type bolt. (See Fig. 5.)

Latch-operating means 20 is operable from the outside of the door by means of handle 29. It comprises a normal retracted latch-operating member 30 projectible through an aperture in door rail 15 against the pressure of a retaining spring to engage bolt 22 and swing the same around its pivot 23 to remove the engaging portion 24 of the bolt from the engaging portion 28 of the interlocking knife type bolt of the inside latch-operating device 21.

Edge supporting means 31 for the window pane is carried all the way over against door rail 15 and supports the window pane 18 intermediate the latch-operating devices 20 and 21.

Immediately it will be observed that the placement of the interlocking bolt 22 upon the post and the arrangement of its body substantially parallel to the jamb 13 enables the door rail 15 to shut very closely upon the jamb when the door is closed. Standard clearance need never be exceeded. The interlocking bolt 22 lies largely within the body of the post 10. Moreover, neither does the door rail 15 have to be cut into to accommodate interlocking member 22, nor does any provision for the bolt have to be made on the interior or exterior of the door rail. It is entirely feasible to extend the window pane substantially all the way over against the inner face of door rail 15. The window may therefore be made of the maximum width consistent with the mechanical strength necessary in the upstanding door rails. Clearly this reduces to a veritable minimum the opaque projection due to window pane support, thickness of door rail, door clearance at the jamb, and the jamb wall of the post.

Proceeding further, however, I juxtapose the interlocking members 22 of the latch mechanisms of the adjacent doors 11 and 12 in one and the same post 10. The spring 25 is so formed and mounted as to commonly actuate these interlocking bolts. The width of post 10 is made a minimum consistent with the mechanical strength required of it. Thus the combined opaque projection of the two door rails and the intermediate post is reduced to a veritable minimum.

Constructively, my invention embodies a number of detailed features, many if not all of which contribute toward the great advance achieved. The entire construction is of metal. The post 10 is of channel section and of pressed steel. The interlocking bolts are pressed steel. The sheet metal body of the bolt has its outer end turned inwardly on a substantially complete circle to form a bearing for the pintle 23. (See Fig. 7.) The engaging portion 24 is formed by deflecting the body outwardly and then in-

wardly to form inner and outer oblique engaging faces 32 and 33. The inner extremity is again deflected forwardly to constitute a lug 34 positioned to engage the inner walls of the jamb and limiting the forward projection of the engaging portion 24. The edges of the body are turned inwardly to constitute reinforcing and stiffening side walls 35. The spring 25 is in the form of a bow spring facing inwardly of the body, with ends socketed between the body of the bolt and its side walls 35. The spring therefore requires no other retaining means. The axes 23 are fixed to post 10 close in the angles or corners of the bottom of the channel section of the post. The apertures in the jambs 13 and 14, through which the bolts project, are of a dimension insuring a close fit of the bolts in them, attaining both neatness in appearance and precision of operation. The surfaces of the bolt at each end are substantially concentric with the axis 23, with the result that the aperture is not opened when the bolt is swung.

The door rails 15 and 16 are likewise of sheet metal. They are in the region of the latch mechanisms, substantially of a double Z section as distinguished from the usual angle section or a channel section. The outermost longitudinal branches of the Z section constitute the overlapping portions 16 and 17 of the door. The outer transverse portion 36 constitutes the jamb rail surface of the doors. The intermediate longitudinally-extending portion 37 with the angle 31 attached to the body 36 forms a supporting channel for the window pane 18 and 19. The offset inner transverse portion 38 provides for the accommodation and interaction of the interlocking bolts 22 and 28, of the latch mechanism. The innermost longitudinally-extending portion 39 constitutes an anchorage for the inner paneling 40 of the doors. Above the window ledge, portions 38 and 39 are eliminated, and the door rail takes the form of a simple Z section as shown in Fig. 9. The window pane is supported between support 31 and section 37. This phase of my invention results not only in great economy in manufacture, but also is an important factor in reducing the upper opaque projection of the door rail itself to that minimum consistent with mechanical strength.

The inner latch-operating device, 21, is supported jointly from the inner panel and the door rail 15. A supporting lock plate 41 which carries axis 26 is secured at one end closely against panel 40, is offset outwardly the thickness of section 39 of the door rail to properly position the device 21, then projected along the panel toward the edge of the door, and at the door rail has its outer end bent laterally so that it lies in the angle of the Z section formed by the innermost

portion 39 and the inner body 38 of the Z section. It is appropriately secured in place by screws or otherwise, and reinforces the rail at this point. The bolt 28 projects 5 neatly and accurately through an aperture in the door rail 15, and the lock plate 41, and is strongly braced laterally by the walls of this aperture and securement on its axis 26. Moreover, lower stop 28^b, constituted by the 10 lower walls of the aperture and an inturned flange on the lock plate 41, retain the bolt 28 in a position on a line between its axis 26 and the engaging portion 24 of bolt 22. So braced, it functions as a keeper in its co- 15 action with bolt 22 at all times except those when it is caused to function as a bolt by operation of handle 27 to move it upwardly about its axis. An upper stop 28^c, struck from lock plate 41, limits the upward movement. The engaging faces of the knife-type bolt 28 are oppositely inclined as respects its longitudinal plane whereby when the door is slammed or pushed shut without the use 20 of handle 27, bolt 28 ratchets past the engaging portion 24 of bolt 22 and the door is latched; and whereby when it is latched, the oppositely inclined engaging faces of the bolt 22 and the bolt 28, under the urge of spring 25, prevent lost motion and rattle of 25 the door. These engaging faces are preferably complementary.

The outside latch-operating device 20 is likewise of pressed metal (see Fig. 3). It is built upon lock plate 42 secured by a laterally and outwardly-extending flange screwed or otherwise fastened to body 36 of the door rail. A bridge 44 bears against the outer panel of the door and is mounted upon the lock plate 42. The handle 29 is journaled 35 between the lock plate and the body. The retaining plate 45 is interposed between the bridge 44 and the lock plate 42. Latch-operating member 30 is retained against the lock plate by this member 45. The operating member comprises a flat body formed 40 of two super-posed plates of metal welded or otherwise secured together. A substantially rectangular aperture 46 extends through the body of the plates as shown in Fig. 4. The inner one of them is provided 45 with a lateral extension 47 which is turned back upon itself as shown in Figs. 2 and 4 to form the rounded engaging end 30^a which contacts with bolt 22. Within the aperture 50 46 is mounted on the spindle of handle 29 a roll back 48 of cam form. This may be of any one of a number of forms adapted to move the operating device 30 in any one of a number of ways, when the operating handle 29 is turned in either or both directions. I have shown, however, a form adapted to move the operating member 30 only when the handle is turned clock-wise, viewed as 55 in Fig. 4. The roll back here is provided 60 with oppositely-extending engaging nibs 50'

and 52'. Aperture 46 is so formed on the side toward the jamb of the door as to constitute on its walls a vertical engaging face 50, and inclined engaging faces 51 and 52, lying in the corner of the aperture and forming an obtuse angle facing the corner. The roll back has its faces on that side shaped complementally and normally lying contiguous to the faces 50, 51 and 52 of device 30. When it is attempted to operate the roll-back counter-clockwise, interlocking engagement of the faces 50 and 51 precludes movement, but when the operating handle 29 is turned clockwise, engagement on faces 50 and 51 is discontinued, and engagement on face 52 is furthered by the nib 52' in a cam action which projects operating member 30 to operate the bolt 22. It is understood, of course, that there is sufficient lost motion and clearance between the parts to permit the roll back to clear the faces 50 and 50', when clockwise rotation is imparted to it, though such lost motion and clearance are not shown in Fig. 4.

Co-acting with the roll back and its reTRACTING SPRING 53 is an adjustable stop 54 in the form of a screw threaded from the exterior of the device concentrically of spring 53 into a boss 55 carried by the flange 43, of the lock plate 42. Both spring 53 and this adjusting screw 54 engage the member 30 through an upstanding lug 56. The engaging end 47 of member 30 may be projected forwardly only such distance as is measured by the space between the end of the adjusting screw 54 and lug 56 at any time. Limiting the degree of projection of the end 47 of member 30 limits the degree of movement of bolt 22. This accomplishes two ends. It prevents such extreme movement of bolt 22 as may preclude the simultaneous opening of an adjacent door when it is sought to open both doors simultaneously. It also enables the extreme projection of member 30 to be so set as to secure ample movement of bolt 22 (engaging as it does near its pivot) and yet not project so far as either to enter the bolt aperture in the post (which would prevent the doors being opened) or to overlap the outer face of the post when it is sought to close it while holding the handle 29 over (which would preclude its closing and mar the face of the post).

A lever 57 is pivoted on the exterior of the retaining plate 45 and has one end projecting through the frontal flange of the latch plate 42 and the door rail 15, while the opposite end lies adjacent a lug 58 projected upwardly from operating member 30. This lever is provided with a depression 59 in its under face coacting with a pair of rises 60 on the retaining plate 45 and is borne closely down upon these rises by close securement upon its pivot, so that the resiliency of its body causes it to snap from one rise 60 to the

other. When on one of them it lies in the path of movement of lug 58 and precludes operation of the latch-operating device, and member 30 is thereby locked against movement by roll back 48. When on the other, it is free of the path of movement of lug 58. When one desires to lock a door against opening from the exterior, he has only to open the door, move the device 57 to carry its end into the path of lug 58 and then close the door, whereupon it can only be opened from the interior through operation of the interior latch-operating device 24. Thus a key-controlled mechanism need be provided for but one of the several doors of a sedan body. All of the other doors can be locked by these means.

Lug 58 is preferably struck from the outer of the plates composing member 30 and is accommodated in the jog in the retaining plate 45 as shown in Fig. 3 whereby it does not interfere with movement of member 30 as long as member 57 is in its upper position. Struck from the inner plate composing member 30 is a lug 61, inturned through an aperture in lock plate 42, as shown in Fig. 2. This aperture is of such dimension as to enable lug 61 to constitute a limit stop which limits the outward projection of the engaging end 30^a of member 30 to a predetermined maximum. This stop functions in case adjustable stop 54 is not used. Lug 56 co-operating with stop 54 is also struck from one of the plates composing member 30, preferably the upper plate. In addition to co-action with adjustable stop 54 upper end of the lug 56 engages abutment 56^a in the form of a reinforcing plate underlying the top of the bridge 44. It is through the co-action of the upper end of lug 56 with the abutment 56^a that lug 56 limits the inward travel and sets the normal position of operating member 30. The inner end of the aperture in which lug 61 projects may be utilized to serve the same purpose by proper adjustment of the dimension of the aperture.

Screw holes 56^b in 56^a serve for anchoring the bridge to the front of the door and the attachment of the escutcheon of handle 29.

In Fig. 8, I show a modification of the inter-locking bolt 22^a and the projecting spring 25^a. The bolt is modified by providing its outer engaging face lying between the pintle 23^a and the engaging end 24^a with a re-entrant section 62 of such depth that there is no danger that the angle of the door-rail formed by sections 36 and 37 can engage the face of the plate and cause opening of the door in case of extreme relative movement between the door and the door-post under rough running conditions. Spring 25^a, in this embodiment, is freed of all contact with bolt 22^a and its pintles 23^a excepting at its extreme ends which are turned out-

wardly a sufficient extent to engage in the bottoms of the pockets within the engaging portions 24^a of the bolts.

It will have been seen that the detail constructional features also contribute a share, albeit a minor share, in the total reduction of the opaque projection in the line of vision. For through this construction it is possible to obtain maximum mechanical strengths with minimum cross sections of the parts.

An invention of this character is subject to many modifications without in any wise departing from its generic spirit of substantially lessening the degree of advantages obtained. Thus the form of the interlocking member 22 and its type may be varied largely. One or more of them may be used, some of one form and type, some of another. So also the form of the latch-operating device 20 may be varied. So, too, the form and type of the latch-operating device 21 may be any one of a large number. And changes in the form of the elements themselves may rise out of these changes of the main groups of the combination or independently thereof. And of course the application may be made to any form or type of body construction of the vehicle or other structure to which the invention is applied. The prime objects of the invention, to wit, utilization of full width of the window and reduction of the opaque projection of the body parts, are obtained in any case. The claims are intended to cover any and all such modifications in addition to the particular embodiment which I have disclosed.

Having thus described my invention, what I claim as new and useful and desire to secure by Letters Patent is:

1. A latch mechanism comprising a horizontally swinging bolt adapted to be mounted on a door jamb, a latching member co-acting with said bolt adapted to be mounted on and extend longitudinally of the door, and means for operating said bolt also adapted to be mounted on the door.

2. A latch mechanism comprising a bolt adapted to be mounted on a door jamb, and dual bolt-engaging means for rendering said bolt inoperative adapted to be operated from the inside and outside of the door respectively.

3. A latch mechanism comprising a bolt adapted to be mounted on a door jamb, dual means for rendering said bolt inoperative operable from either the inside or outside of the door adapted to be carried by the door and to engage the bolt at points laterally spaced apart.

4. The combination with a door post, and a latch bolt mounted thereon, of a door co-operating with the door post, and means arranged upon said door at opposite sides thereof operable independently of each other for engaging said bolt.

5. The combination with a door post, and a latch bolt mounted thereon, of a door adapted to have a sliding window pane arranged therein, and dual means for engaging said bolt independently of each other located at opposite sides of the door, so that the window pane may be disposed therebetween.

6. A latch mechanism comprising two separated latch operating devices, one operable from the inside of the door and the other from the outside of the door, and an interlocking member between said devices and with which intermediary said devices co-act, and which interlocking member is adapted to be located on the jamb of the door.

7. A latch mechanism comprising two separated latch operating devices adapted to be operated one from the inside and one from the outside of a door, and an interlocking member engaged by each of said devices and with which intermediary said devices co-act, and which interlocking member is adapted to be located on the jamb of a door post.

8. In combination, a door, a door post constituting a jamb, two separated latch operating devices one on the inside and one on the outside of the door adapted to have a window glass interposed therebetween, and an interlocking member mounted on the post and with which intermediary said separated latch operating devices co-act to latch and unlatch the door.

9. In combination, a door post constituting a jamb, a door having a jamb rail substantially parallel to the jamb, laterally spaced latch engaging devices having engaging members projecting through the body of said door rail, an interlocking member on the door post with which intermediary said spaced latch engaging devices co-act to latch and unlatch the door, said latch engaging devices being adapted to have a window pane interposed therebetween, the edges of which lie substantially against the body of the door rail.

10. In combination, a door post constituting a jamb, a door having a jamb rail of sheet metal having its body substantially parallel to the jamb, laterally spaced latch engaging devices having engaging members projecting through the body of said sheet metal door rail, an interlocking member on the door post with which intermediary said spaced latch engaging devices coact to latch and unlatch the door, said latch engaging devices being adapted to have a window pane interposed therebetween, the edges of which lie substantially against the body of the door rail.

11. A latch mechanism comprising interlocking latch bolts, one adapted to be mounted on a door and the other adapted

to be mounted on a door post, together with two operating means one for each bolt, both of said operating means being mounted on the door.

12. A latch mechanism comprising interlocking latch bolts, one adapted to be mounted on a door and the other adapted to be mounted on a door post, together with two operating means, one for each bolt, both of said means being carried by the door, one being operable from the inside of the door and the other from the outside.

13. In a latch mechanism, a pair of interlocking latch bolts, and latch operating devices for the respective bolts, both adapted to be mounted upon a door and in spaced relation to each other whereby a window glass may be raised and lowered between them.

14. A latch mechanism comprising a pair of interlocking latch bolts, one of which is a swinging bolt and adapted to be mounted on the door jamb, and the other of which is adapted to be mounted on the door, and separate operating means for the respective bolts, both adapted to be mounted on the door.

15. A latch mechanism comprising a pair of interlocking latch bolts, one swinging in a horizontal plane and adapted to be mounted on the door post and the other swinging in a vertical plane and adapted to be mounted on an associated door, together with operating devices for the respective bolts, both adapted to be mounted on the door.

16. In combination, a door, a door post constituting a jamb, a horizontally swinging latch bolt mounted on the door post, a latch operating device including a roll back mounted on the outside of said door, a latch engaging device comprising a knife bolt mounted on the inside of said door, said door adapted to have a window glass slidably arranged therein between said latch operating devices.

17. In combination, a sheet metal door post of angle section, one face of which constitutes the door jamb, and a horizontally swinging latch bolt mounted on and operating through an aperture in said jamb face of the post.

18. In combination, a sheet metal door post of angle section, one face of which constitutes the jamb and the other the exterior, and an inwardly facing horizontal swinging latch bolt mounted on said post having its outer end hinged in the bend of the post angle, and its inner end projecting through an aperture in the jamb.

19. In combination, a sheet metal door post of angle section, having one face constituting a jamb and the other the exterior, together with a horizontal swinging latch bolt hinged interiorly of said angle and

having its engaging end projected through an aperture in the jamb.

20. In combination, a door post of channel section, the base of which constitutes the exterior of the post and the sides of which constitute the door jambs, and juxtaposed horizontally swinging latch bolts hinged interiorly of said channel and having engaging ends projected through apertures in the sides thereof, together with a common latch spring between them.

21. A latch mechanism comprising a bolt, operating means therefor including a laterally projecting lug, and an adjustable stop arranged in the path of movement of said operating means and engaging said lug whereby to limit the degree of operation of the bolt.

22. In an automobile door construction including a main body adapted to have an extensible portion therein, said main body having a latch mechanism including portions carried thereby respectively inside and outside of the path of movement of said extensible portion, and an interlocking element between the inside and outside portions of said latch mechanism portion lying without the jamb face of the door when the same is closed, said jamb face being provided with an inward offset or recess within which said interlocking element is accommodated when the door is closed.

23. In a latch mechanism for an automobile door adapted to have an extensible member of substantially the full width of the body of the door adapted for slidable movement in said door with the side edge thereof in close proximity to the jamb rail of the door, inside and outside door releasing mechanisms carried by the door on opposite sides of the path of movement of said extensible member, and a device through the intermediary of which said door releasing mechanisms act to unlatch the door, which device is mounted upon the door post and extends across the projected plane of said extensible member whereby the door may be opened and controlled by one hand as in the usual practice.

24. A latch mechanism for an automobile door adapted to have an extensible member of substantially the full width of the body of the door adapted for slidable movement in said door with the side edge thereof in close proximity to the jamb rail of the door, comprising inside and outside operating mechanisms carried by the door on opposite sides of the path of movement of said extensible member, and a device mounted independently of the door through the intermediary of which said operating mechanisms act to unlatch the door, the main body of said device lying closely adjacent the jamb face of the door itself.

25. A latch mechanism for an automobile

door adapted to have an extensible member of substantially the full width of the body of the door adapted for slidable movement in said door with the side edge thereof in close proximity to the jamb rail of the door, comprising inside and outside operating mechanisms carried by the door on opposite sides of the path of movement of said extensible member and an interconnecting device between said operating mechanisms, said interconnecting device partaking of a movement different in character from the movements of said operating mechanisms.

26. A latch mechanism for an automobile door adapted to have an extensible member of substantially the full width of the body of the door adapted for slidable movement in close proximity to the jamb rail of the door, comprising inside and outside latch operating mechanisms and an interlocking device between said mechanisms, said operating mechanisms engaging said interlocking device at points lying respectively on opposite sides of the projected path of movement of the extensible member, and said operating mechanisms and interlocking device being mounted on the door and door post, respectively.

27. A latch operating mechanism comprising two separated latch operating devices adapted to be operated one from the inside and one from the outside of a door, and an interlocking member between said devices, one of said operating devices coacting with said interlocking member in the fashion of a bolt and keeper and the other operating device engaging said interlocking member to retract the same.

28. In a latch mechanism for an automobile door adapted to have an extensible member slidably arranged therein, a dual operating mechanism carried by the door on opposite sides of the path of movement of said extensible member, and a device through the intermediary of which said operating mechanisms act to unlatch the door, said device being borne on bearings located within the body of the door post.

29. In a latch mechanism for an automobile door adapted to have a sliding window of substantially the full width of the body of the door, two separated latch operating devices operable from the inside and outside of the door respectively, and an interlocking member between said devices, said interlocking member having portions located on opposite sides of the projected path of movement of the sliding window, said portions projecting toward the jamb face of the door from the jamb face of the post.

30. A latch mechanism for a door, the jamb rail of which is rabbetted, comprising dual operating mechanisms located on opposite sides of the door, an interlocking

member interconnecting said operating devices carried by the door post, said interlocking member having a part thereof projecting normally into said rabbet for engagement with one of said operating mechanisms.

31. In a latch mechanism for an automobile door having a stamped metal jamb rail of single thickness against the face of which one edge of a sliding window is adapted to move, inside and outside operating devices located on opposite sides of the path of movement of said sliding window, and an interlocking member between said operating devices, said interlocking member lying closely adjacent the outer face of said stamped metal rail and being carried by the door post.

32. In a latch operating mechanism for an automobile door having a stamped metal jamb rail of single thickness upon the inner face of which is adapted to have mounted a glass run channel for a sliding window, a pair of operating members carried by the door, and disposed on opposite sides of the path of movement of said window, and an interlocking device between said operating members carried by the door post, said operating members and interlocking device combining to form a latch operating mechanism of substantially U-form embracing said glass run channel.

33. In combination, a door post of channeled section, the base of which constitutes the exterior of the post and the sides of which constitute the door jambs, an associated door having a jamb rail of substantially Z section upon the inner face of which is mounted a glass run channel, a latch operating mechanism having one element thereof carried by the post, and inside and outside operating mechanisms carried by the door, said latch operating mechanism being arranged such that it embraces said glass run channel.

34. In combination, a door post of channeled section, the base of which constitutes the exterior of the post and the sides of which constitute the door jambs, a pair of associated doors having jamb rails of substantially Z section, the outer branches of said Z sections constituting the outer overlaps of the doors, said overlaps being substantially contiguous at the median plane of the post and the post being of a width not exceeding the combined width of said overlaps, inside and outside latch operating devices carried by each of said doors, and oppositely pressed interlocking members between said inside and outside operating devices supported on the opposed jamb faces of the door post.

35. In combination with an automobile

door adapted to have a sliding window arranged therein of a width substantially of the full width of the door and posts therefor, inside and outside operating mechanisms for a latch bolt disposed on opposite sides of the path of movement of said sliding window, and an interlocking device between said operating mechanisms circumventing the side edge of said path of movement, said interlocking device being carried by said door post.

36. In an automobile door adapted to have a sliding window arranged therein of a width substantially of the full width thereof and a door post, in combination, inside and outside latch operating devices carried by said door, and an interlocking member interconnecting said devices, said member being carried by the door post in such manner that its main body portion lies between said post and its adjoining door.

37. In combination an automobile door adapted to have, a slidable window substantially the full width of the body of the door adapted for sliding movement therein with the side edge thereof in close proximity to the jamb rail of the door, inside and outside latch operating devices carried by the door on opposite sides of the plane of movement of said sliding window, a door post and an interlocking member carried by the door post and coacting with the inside and outside latch operating devices in such manner that the door may be unlatched from the outside or the inside.

38. In combination, a door post and an adjoining door, a latch element carried by said door post and having a portion thereof projecting within the plane of the jamb rail of said door for interlocking engagement with a latch member carried by the door, and a device for actuating said first named latch element also carried by said door but spaced from said last mentioned latch element, whereby to provide for the accommodation of a sliding window in said space.

39. In combination, an automobile door adapted to have a sliding window arranged therein of a width substantially of the full width thereof and a rabbeted jamb rail, a door post, and latch operating mechanisms on opposite sides of the plane of movement of said sliding window, and an interlock interconnecting said operating mechanisms, said interlock being carried by the door post and having a portion thereof projecting into the rabbet of said door for interlocking engagement with one of said operating mechanisms.

In testimony whereof, I affix my signature.

JOSEPH LEDWINKA.
